(57) **ABSTRACT**

A method of producing the floor-bridging units, which increases production rate of the floor-bridging units. First rough lumber beams are fed through a planer, which planes the lumber to the required consistent size tolerance. The planed lumber is transferred to a cut-off saw to cut the legs. The legs are transferred to a dado machine and a dado slot is cut into the lumber. The legs are transferred to a joining station to form the X member, where the dado slots are joined into a dado joint by gluing and stapling the joint. The X member is transferred to a trimming station to be trimmed. At the same time flanges are being made by cutting sheet lumber in strips and then into rectangles to form the flanges. The flanges are transferred to a nailing jig, while glue is applied to the trimmed ends of the legs of the X members. The X members with the applied glue are transferred to the nailing jig. Finally, the flanges are nailed to the glued ends of the X members and the finished floor-bridging units are transferred to a packaging area.

METHOD OF ASSEMBLING A FLOOR-BRIDGING UNIT

This application claims the benefit of U.S. Provisional Application No. 60/215,624, filed Jun. 30, 2000 and hereby incorporates it by reference.

BACKGROUND

Floor-bridging units **10** are used for framing floors of wood buildings. FIG. 1 shows an example of a floor-bridging unit **10**. The floor-bridging unit **10** is generally an X shaped member **12** with flanges **14** attached to two sides **16**. The floor-bridging units **10** are placed between floor joists **18** and nailed through the flange **14** to the joist **18**, as seen in FIG. 2. Once installed in rows between the joists **18**, they transmit point loads from one joist **18** to the adjacent joists **18** by supplying support to the joists **18** in compression or tension. The floor-bridging units **10** add stiffness and rigidity to the floor system. The increase in rigidity and stiffness allows for longer joist spans, shallower joists **18**, or wider on-center joists **18**, thereby providing for more cost-effective material usage.

The floor-bridging unit **10** is usually constructed by creating the X member **12** from two legs **22** of #2 grade kiln dried spruce 2x3s. The 2x3 are each planed to tolerance, mitered on the ends and dado cut at the center to remove a portion of material from each piece, as shown in FIG. 3. The two dado cut slots **24** are then joined together with glue and staples to form the X member **12** of the floor-bridging unit **10**. The $\frac{3}{4}$ " Douglas Fir plywood flanges **14** are then glued and nailed to the ends of the X member **12** to form the floor-bridging unit **10**, as shown in FIG. 1. Current industry practices are to first plane the 2x3 lumber for the legs **22** and then to cut the lumber to length using a hand operated miter saw. The 2x3 lumber is actually about 1 and $\frac{1}{2}$ inches by 2 and $\frac{1}{2}$ inches and is planed down to a consistent 1 and $\frac{1}{2}$ inches by 2 and $\frac{7}{16}$ inches. The lumber is planed because initially the lumber is not a consistent size and needs to be in order to maintain the manufacture of a quality product. Once cut to length, the dado slot **24** is cut into the legs **22** by a saw. Two legs **22** are joined at the dado slots **24** to create a dado joint and form the X member **12**. This joint is glued and stapled together. The ends of the joined legs **22** are trimmed to tolerance in a table saw. To make the flanges **14**, sheet wood is cut into strips and then into rectangles on a table saw. Glue is then applied by hand to the four ends of the dado joined legs **22** of X member **12**. After the glue is applied, the rectangles are positioned onto the ends by hand and nailed in place using a hand operated nail gun.

It is an object of the present invention is to provide a method of mass producing floor-bridging units **10** in an efficient and cost effective manner.

SUMMARY OF THE INVENTION

A method of producing the floor-bridging units, which increases production rate of the floor-bridging units. First rough lumber beams are fed through a planer, which planes the lumber to the required consistent size tolerance. The planed lumber is transferred to a cut-off saw to cut the legs. The legs are transferred to a dado machine and a dado slot is cut into the lumber. The legs are transferred to a joining station to form the X member, where the dado slots are joined into a dado joint by gluing and stapling the joint. The X member is transferred to a trimming station to be trimmed. At the same time flanges are being made by cutting sheet lumber in strips and then into rectangles to form the flanges.

The flanges are transferred to a nailing jig, while glue is applied to the trimmed ends of the legs of the X members. The X members with the applied glue are transferred to the nailing jig. Finally, the flanges are nailed to the glued ends of the X members and the finished floor-bridging units are transferred to a packaging area.

BRIEF DESCRIPTION OF THE DRAWINGS

FIG. 1 is a perspective view of a floor-bridging unit;

FIG. 2 is a perspective view of a leg of the floor-bridging unit;

FIG. 3 is a perspective view of installed floor-bridging units;

FIG. 4 is a top schematic view of cutting the legs according to the present invention;

FIG. 5 is a top schematic view of trimming an X member according to the present invention;

FIG. 6 is another top schematic view of trimming the X member according to the present invention;

FIG. 7 is a top schematic view of a different method of trimming the X member according to the present invention;

FIG. 8 is a top schematic view of the X member on a nailing jig according to the present invention.

DETAILED DESCRIPTION

The present invention is a method of producing the floor-bridging units **10**, which increases production rate of the floor-bridging units **10**. First rough lumber beams are fed through a planer, which planes the lumber to the required consistent size tolerance. The planed lumber is transferred to a cut-off saw to cut the legs **22**. The legs **22** are transferred to a dado cutting station and a dado slot **24** is cut into the lumber of the leg **22**. The legs **22** are transferred to a joining station to form the X member **12**, where the dado slots **24** are joined into a dado joint by gluing and stapling the joint. The X member **12** is transferred to a trimming station to be trimmed. At the same time flanges **14** are being made by cutting sheet lumber in strips and then into rectangles to form the flanges **14**. The flanges **14** are transferred to a nailing jig at a nailing station, while glue is applied to the trimmed ends of the legs **22** of the X members **12**. The X members **12** with the applied glue are transferred to the nailing jig. Finally, the flanges **14** are nailed to the glued ends of the X members **12** and the finished floor-bridging units **10** are transferred to a packaging area. The following is a detailed description of the method of the present invention.

There are two parallel lines that join up for the final assembly of the floor-bridging units **10**. A first line is the 2x3 processing line. A second line is the flange processing line. The nailing jig is at the end of the first and second lines, where the final assembly of the floor-bridging units **10** takes place. At the beginning of the first line, rough shaped 2x3

lengths of lumber are currently planed on two sides to provide a consistent size. The planed 2x3 lengths of lumber are then transferred to a cut-off saw on in-feed rollers. At the cut-off saw the leading end of each length of lumber is angle cut as shown in FIG. 4. An adjustable stop is positioned further down from the cut-off saw to produce legs **22** of the same length. The angle cut end is butted against the stop and the lumber is angle cut to produce a leg **22**. The leg **22** is removed and the remaining lumber is moved against the stop to cut another leg **22**. The angle cut is approximately close to the actual angle needed on each end of the leg **22**, which saves on lumber waste. When the legs **22** are removed from

the cut-off saw, the legs 22 are placed on a conveyer to move the legs 22 to a dado cutting station. After cutting of the legs 22 to length and before dado cutting of the legs 22, the first end of the legs 22 which rested against the stop is marked with a felt tip marker to index the legs 22.

Each leg 22 is positioned in the dado machine, such that each indexed end of each leg 22 is located in the same position on the dado machine, and the dado slot 24 is cut. The indexed ends of the legs 22 are matched during the assembly of two legs 22 into the X member 12, such that the indexed ends are on the same side of the X member 12 that is formed. The two legs 22 are glued together at the dado slot 24. After the glue has been applied and the pieces properly fit, the joint is stapled. The X members 12 are then moved to a table saw to be trimmed. The table saw includes a left fence and a right fence, as shown in FIGS. 5-6. First the index ends are placed against the left fence and the right side of the X member 12 is trimmed, such that the distance between the center of the X member 12 and the trimmed right side is the required center to side length. The X member 12 is then moved such that the newly trimmed right side is positioned against the right fence, so that the left side can be trimmed. Finally, the left side of the X member 12 is trimmed, such that the distance between the center of the X member 12 and the trimmed left side is the required center to side length. The finished X member 12 is then placed on a conveyer and moved to the nailing jig.

An alternative to trimming the X member 12 with a table saw and two fences of FIGS. 5-6 is to use a double head radial arm saw having two saw heads. The double head radial arm saw is shown from a top view in FIG. 7. The double head radial arm saw includes a table, fence, a fix head and a movable head. The fixed head and the movable head each include a saw blade to cut the legs 22 of the X member 12 to size. The fence is secured on the table and positioned outside of the fixed head. The fixed head moves in the Y direction, but is fixed in the Z direction. The movable head moves in the Y direction and is adjustable in the Z direction. The fixed head and movable head move in the Y direction together in unison during the cutting process, whereby the saw blades of the heads cut in the Y direction. The heads can be moved using either a manual or automated system. The object is to assemble the legs 22 to form the X member 12, whereby a desired distance A from tip to tip, shown in FIG. 2, is maintained so that the floor-bridging unit 10 is a desired size when completed. The desired size depends on the spacing of the floor joists 18 that the floor-bridging unit 10 will be between. As shown in FIG. 3, a distance B from the tip of the index end to the dado slot 24 of each leg 22 is known, which is usually longer than needed. The known distance B allows for setting up and consistently trimming the legs 22 on the double head radial arm saw. The fence is secured to the table at a distance outside the fixed head, whereby when the indexed ends of the X member 12 are placed against the fence, the distance from the center of the X member 12 to the saw blade of the fixed head is one half of the desired distance A. The movable head is then positioned in the Z direction, such that the distance of the center of the X member 12 to the saw blade of the movable head is one half of the desired distance A. Once the fence and heads are positioned and the X member 12 is placed on the table, the heads are moved in the Y direction to cut off the ends of the X member 12.

Meanwhile, 4 foot×8 foot sheets of plywood are stacked four high and ripped lengthwise into $3\frac{1}{16}$ inch wide strips in a programmable panel saw. The $3\frac{1}{16}$ inch wide strips four high are cut to length in the same machine to form the

flanges 14. The finished flanges 14 are then moved on a conveyer to the nailing jig. Flanges 14 and the X members 12 are joined using the following procedure, as shown in FIG. 8. At the nailing station, two flanges 14 are placed in the nailing jig in position A, as shown in FIG. 8. Glue is applied onto the ends of the X member 12 either manually or using a glue application device. The X member 12 is placed in the nailing jig between the flanges 14. There are two sets of four automated nail guns to join the flanges 14 and the X members 12, where one set is at position A and the other set is at position B. At position A, the forward nail guns are at an angle to the flanges 14 and the rearward nail guns are straight on at the flanges 14. When fired, the forward nail guns shoot the nails into the flanges 14 and legs 22 on an angle and the rearward nail guns shoot the nails straight into the flanges 14 and legs 22. After nailing at position A, the semi-assembled floor-bridging unit 10 is slid to position B. At position B, the rearward nail guns are at an angle to the flanges 14 and the forward nail guns are straight on at the flanges 14. When fired, the rearward nail guns shoot the nails into the flanges 14 and legs 22 on an angle and the forward nail guns shoot the nails straight into the flanges 14 and legs 22. Finished floor-bridging units 10 are stacked and sent to final packaging. At final packaging, the floor-bridging units 10 are nested, an installation guide is added, and the bundle is banded together. Bundles are stacked on a pallet and stretched-wrapped when full.

While different embodiments of the invention have been described in detail herein, it will be appreciated by those skilled in the art that various modifications and alternatives to the embodiments could be developed in light of the overall teachings of the disclosure. Accordingly, the particular arrangements are illustrative only and are not limiting as to the scope of the invention which is to be given the full breadth of any and all equivalents thereof.

We claim:

1. A method of producing a floor-bridging unit, the floor-bridging unit including a X member of two legs, two flanges attached to sides of the X member and where a distance A between the flanges is a desired distance which sets the size of the floor-bridging unit, the method comprising:

cutting legs to a desired length, the desired length of each leg being long enough to produce the X member having the distance A between the flanges;

indexing one end of each leg, such that the same end of each leg is indexed in relation to the cutting of the legs for assembly of the floor-bridging unit;

cutting a dado slot near the middle of each leg to remove material in each leg, the dado slot being a set distance from the indexed end of each leg;

assembling the X member by assembling two legs together at the dado slot of each leg to form the X member, such that the indexed end of each leg is on the same side of the X member;

trimming the sides of the assembled X member which receive the flanges, such that the distance between the sides are the distance A;

applying glue to the sides of the assembled X member which receive the flanges;

placing the X member in a nailing station of a plurality of nail guns;

positioning the flanges against the sides of the X member; and

nailing the flanges to the sides of the X member.

2. The method of claim 1, wherein indexing of the legs is done by marking the end of the legs.

3. The method of claim 1, wherein trimming of the X member is accomplished by using a table saw; wherein the table saw includes a left fence and a right fence; wherein the X member is placed on the table of the table saw such that the index ends are placed against the left fence; wherein the right side of the X member is trimmed by running the index ends along the left fence and the right side through a saw blade of the table saw; wherein the distance between the center of the X member and the trimmed right side is one half of the distance A; wherein the X member is then moved such that the newly trimmed right side is positioned against the right fence, so that the indexed ends can be trimmed; and wherein the indexed ends of the X member is trimmed by running the ends of the trimmed right side along the right fence and the indexed ends through a saw blade of the table saw, such that the distance between the center of the X member and the trimmed indexed ends is one half of the distance A.

4. The method of claim 1, wherein trimming of the X member is accomplished by using a double head radial arm saw having two saw heads; wherein the double head radial arm saw includes a table, fence, a fix head and a movable head; wherein the table has a length and a width; wherein the fixed head and the movable head each include a saw blade to cut the legs of the X to size; wherein the fence is secured on the table along the width and positioned outside of the fixed head; wherein the fixed head moves in the width direction, but is fixed in the length direction; wherein the movable head moves in the width direction and is adjustable in the length direction; wherein the fixed head and movable head move in the width direction together in unison during the cutting process; wherein the saw blades of the heads cut in the width direction; wherein the fence is secured to the table at a distance outside the fixed head, whereby when the indexed ends of the X are placed against the fence, the distance from the center of the X to the saw blade of the fixed head is one half of the desired distance A; wherein the movable head is then adjusted and fixed in the length direction, such that the distance of the center of the X to the saw blade of the movable head is one half of the desired distance A; wherein the X member is placed on the table, such that the indexed ends are against the fence; and wherein the heads are moved in the width direction to cut off the ends of the X.

5. The method of claim 1, wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward and wherein nails are fired into the flanges at position A and the X member and the flanges are moved to position B where 55 nails are fired into the flanges to assemble the floor-bridging unit.

6. The method of claim 1, wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward; wherein at position A the forward nail guns are at an angle 60 to the flanges and the rearward nail guns are straight on at the flanges, such that when the guns at position A are fired,

the forward nail guns shoot the nails into the flanges and legs on an angle and the rearward nail guns shoot the nails straight into the flanges and legs; wherein the nails are fired into the flanges at position A; wherein after nailing at position A, a semi-assembled floor-bridging unit is slid to position B; wherein at position B, the rearward nail guns are at an angle to the flanges and the forward nail guns are straight on at the flanges, such that when fired, the rearward nail guns shoot the nails into the flanges and legs on an angle and the forward nail guns shoot the nails straight into the flanges and legs; and wherein the nails are fired into the flanges at position B.

7. The method of claim 1,

wherein trimming of the X member is accomplished by using a table saw; wherein the table saw includes a left fence and a right fence; wherein the X member is placed on the table of the table saw such that the index ends are placed against the left fence; wherein the right side of the X member is trimmed by running the index ends along the left fence and the right side through a saw blade of the table saw; wherein the distance between the center of the X member and the trimmed right side is one half of the distance A; wherein the X member is then moved such that the newly trimmed right side is positioned against the right fence, so that the indexed ends can be trimmed; and wherein the indexed ends of the X member is trimmed by running the ends of the trimmed right side along the right fence and the indexed ends through a saw blade of the table saw, such that the distance between the center of the X member and the trimmed indexed ends is one half of the distance A; and wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward; wherein at position A the forward nail guns are at an angle to the flanges and the rearward nail guns are straight on at the flanges, such that when the guns at position A are fired, the forward nail guns shoot the nails into the flanges and legs on an angle and the rearward nail guns shoot the nails straight into the flanges and legs; wherein the nails are fired into the flanges at position A; wherein after nailing at position A, a semi-assembled floor-bridging unit is slid to position B; wherein at position B, the rearward nail guns are at an angle to the flanges and the forward nail guns are straight on at the flanges, such that when fired, the rearward nail guns shoot the nails into the flanges and legs on an angle and the forward nail guns shoot the nails straight into the flanges and legs; and wherein the nails are fired into the flanges at position B.

8. The method of claim 1,

wherein trimming of the X member is accomplished by using a double head radial arm saw having two saw heads; wherein the double head radial arm saw includes a table, fence, a fix head and a movable head; wherein the table has a length and a width; wherein the fixed head and the movable head each include a saw blade to cut the legs of the X to size; wherein the fence is secured on the table along the width and positioned outside of the fixed head; wherein the fixed head moves in the width direction, but is fixed in the length direction; wherein the movable head moves in the width direction and is adjustable in the length direction;

wherein the fixed head and movable head move in the width direction together in unison during the cutting process; wherein the saw blades of the heads cut in the width direction; wherein the fence is secured to the table at a distance outside the fixed head, whereby when the indexed ends of the X are placed against the fence, the distance from the center of the X to the saw blade of the fixed head is one half of the desired distance A; wherein the movable head is then adjusted and fixed in the length direction, such that the distance of the center of the X to the saw blade of the movable head is one half of the desired distance A; wherein the X member is placed on the table, such that the indexed ends are against the fence; and wherein the heads are moved in the width direction to cut off the ends of the X; and

wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward; wherein at position A the forward nail guns are at an angle to the flanges and the rearward nail guns are straight on at the flanges, such that when the guns at position A are fired, the forward nail guns shoot the nails into the flanges and legs on an angle and the rearward nail guns shoot the nails straight into the flanges and legs; wherein the nails are fired into the flanges at position A; wherein after nailing at position A, a semi-assembled floor-bridging unit is slid to position B; wherein at position B, the rearward nail guns are at an angle to the flanges and the forward nail guns are straight on at the flanges, such that when fired, the rearward nail guns shoot the nails into the flanges and legs on an angle and the forward nail guns shoot the nails straight into the flanges and legs; and wherein the nails are fired into the flanges at position B.

9. A method of producing a floor-bridging unit, the floor-bridging unit including a X member of two legs, two flanges attached to sides of the X member and where a distance A between the flanges is a desired distance which sets the size of the floor-bridging unit, the method comprising:

cutting legs to a desired length, the desired length of each leg being long enough to produce the X member having the distance A between the flanges;

indexing one end of each leg, such that the same end of each leg is indexed in relation to the cutting of the legs for assembly of the floor-bridging unit;

cutting a dado slot near the middle of each leg to remove material in each leg, the dado slot being a set distance from the indexed end of each leg;

assembling the X member by assembling two legs together at the dado slot of each leg to form the X member, such that the indexed end of each leg is on the same side of the X member;

trimming the sides of the assembled X member which receive the flanges, such that the distance between the sides are the distance A;

placing the X member in a nailing station of a plurality of nail guns;

positioning the flanges against the sides of the X member; and

nailing the flanges to the sides of the X member.

10. The method of claim 9, wherein indexing of the legs is done by marking the end of the legs.

11. The method of claim 9, wherein trimming of the X member is accomplished by using a table saw; wherein the table saw includes a left fence and a right fence; wherein the X member is placed on the table of the table saw such that the index ends are placed against the left fence; wherein the right side of the X member is trimmed by running the index ends along the left fence and the right side through a saw blade of the table saw; wherein the distance between the center of the X member and the trimmed right side is one half of the distance A; wherein the X member is then moved such that the newly trimmed right side is positioned against the right fence, so that the indexed ends can be trimmed; and wherein the indexed ends of the X member is trimmed by running the ends of the trimmed right side along the right fence and the indexed ends through a saw blade of the table saw, such that the distance between the center of the X member and the trimmed indexed ends is one half of the distance A.

12. The method of claim 9, wherein trimming of the X member is accomplished by using a double head radial arm saw having two saw heads; wherein the double head radial arm saw includes a table, fence, a fix head and a movable head; wherein the table has a length and a width; wherein the fixed head and the movable head each include a saw blade to cut the legs of the X to size; wherein the fence is secured on the table along the width and positioned outside of the fixed head; wherein the fixed head moves in the width direction, but is fixed in the length direction; wherein the movable head moves in the width direction and is adjustable in the length direction; wherein the fixed head and movable head move in the width direction together in unison during the cutting process; wherein the saw blades of the heads cut in the width direction; wherein the fence is secured to the table at a distance outside the fixed head, whereby when the indexed ends of the X are placed against the fence, the distance from the center of the X to the saw blade of the fixed head is one half of the desired distance A; wherein the movable head is then adjusted and fixed in the length direction, such that the distance of the center of the X to the saw blade of the movable head is one half of the desired distance A; wherein the X member is placed on the table, such that the indexed ends are against the fence; and wherein the heads are moved in the width direction to cut off the ends of the X.

13. The method of claim 9, wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward and wherein nails are fired into the flanges at position A and the X member and the flanges are moved to position B where nails are fired into the flanges to assemble the floor-bridging unit.

14. The method of claim 9, wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward; wherein at position A the forward nail guns are at an angle to the flanges and the rearward nail guns are straight on at the flanges, such that when the guns at position A are fired,

the forward nail guns shoot the nails into the flanges and legs on an angle and the rearward nail guns shoot the nails straight into the flanges and legs; wherein the nails are fired into the flanges at position A; wherein after nailing at position A, a semi-assembled floor-bridging unit is slid to position B; wherein at position B, the rearward nail guns are at an angle to the flanges and the forward nail guns are straight on at the flanges, such that when fired, the rearward nail guns shoot the nails into the flanges and legs on an angle and the forward nail guns shoot the nails straight into the flanges and legs; and wherein the nails are fired into the flanges at position B.

15. The method of claim 9,

wherein trimming of the X member is accomplished by using a table saw; wherein the table saw includes a left fence and a right fence; wherein the X member is placed on the table of the table saw such that the index ends are placed against the left fence; wherein the right side of the X member is trimmed by running the index ends along the left fence and the right side through a saw blade of the table saw; wherein the distance between the center of the X member and the trimmed right side is one half of the distance A; wherein the X member is then moved such that the newly trimmed right side is positioned against the right fence, so that the indexed ends can be trimmed; and wherein the indexed ends of the X member is trimmed by running the ends of the trimmed right side along the right fence and the indexed ends through a saw blade of the table saw, such that the distance between the center of the X member and the trimmed indexed ends is one half of the distance A; and wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward; wherein at position A the forward nail guns are at an angle to the flanges and the rearward nail guns are straight on at the flanges, such that when the guns at position A are fired, the forward nail guns shoot the nails into the flanges and legs on an angle and the rearward nail guns shoot the nails straight into the flanges and legs; wherein the nails are fired into the flanges at position A; wherein after nailing at position A, a semi-assembled floor-bridging unit is slid to position B; wherein at position B, the rearward nail guns are at an angle to the flanges and the forward nail guns are straight on at the flanges, such that when fired, the rearward nail guns shoot the nails into the flanges and legs on an angle and the forward nail guns shoot the nails straight into the flanges and legs; and wherein the nails are fired into the flanges at position B.

16. The method of claim 9,

wherein trimming of the X member is accomplished by using a double head radial arm saw having two saw heads; wherein the double head radial arm saw includes a table, fence, a fix head and a movable head; wherein the table has a length and a width; wherein the fixed head and the movable head each include a saw blade to cut the legs of the X to size; wherein the fence is secured on the table along the width and positioned outside of the fixed head; wherein the fixed head moves in the width direction, but is fixed in the length direction; wherein the movable head moves in the width direction and is adjustable in the length direction; wherein the fixed head and movable head move in the width direction together in unison during the cutting process; wherein the saw blades of the heads cut in the width direction; wherein the fence is secured to the table at a distance outside the fixed head, whereby when the indexed ends of the X are placed against the fence, the distance from the center of the X to the saw blade of the fixed head is one half of the desired distance A; wherein the movable head is then adjusted and fixed in the length direction, such that the distance of the center of the X to the saw blade of the movable head is one half of the desired distance A; wherein the X member is placed on the table, such that the indexed ends are against the fence; and wherein the heads are moved in the width direction to cut off the ends of the X; and

wherein there are two sets of four automated nail guns to join the flanges and the X member; wherein one set is at a position A on the nailing station having two nail guns positioned forward and two nail guns positioned rearward; wherein the second set is at a position B on the nailing station having two nail guns positioned forward and two nail guns positioned rearward; wherein at position A the forward nail guns are at an angle to the flanges and the rearward nail guns are straight on at the flanges, such that when the guns at position A are fired, the forward nail guns shoot the nails into the flanges and legs on an angle and the rearward nail guns shoot the nails straight into the flanges and legs; wherein the nails are fired into the flanges at position A; wherein after nailing at position A, a semi-assembled floor-bridging unit is slid to position B; wherein at position B, the rearward nail guns are at an angle to the flanges and the forward nail guns are straight on at the flanges, such that when fired, the rearward nail guns shoot the nails into the flanges and legs on an angle and the forward nail guns shoot the nails straight into the flanges and legs; and wherein the nails are fired into the flanges at position B.
